[57] CLAIM

The ornamental design for a socket head tool for engaging and manipulating pipe fittings, as shown and described.

DESCRIPTION

FIG. 1 is a top plan view of a socket head tool for engaging and manipulating pipe fittings showing my new design; FIG. 2 is a front elevational view thereof, the rear elevational view being identical;

FIG. 3 is a side elevational view thereof, the opposite side elevational view being identical;

FIG. 4 is a bottom plan view thereof;

FIG. 5 is a perspective view thereof;

FIG. 6 is a side elevational view of a second embodiment of the socket head tool for engaging and manipulating pipe fittings, the opposite side elevational view being identical; and,

FIG. 7 is a front elevational view thereof, the rear elevational view being identical.
